UNITED STATES PATENT OFFICE

2,038,821

SHUTTER CONTROL FOR INTERNAL
COMBUSTION ENGINES

Frederick C. Bargar, Columbus, Ohio, assignor to
Pines Winterfront Company, Chicago, Ill., a
corporation of Delaware

Application March 29, 1929, Serial No. 351,003
Renewed April 20, 1931

10 Claims. (Cl. 123—174)

The present invention relates to shutter controls for internal combustion engines, and is particularly concerned with shutters adapted to be controlled responsive to a plurality of actuating devices.

It is highly desirable in a shutter control that the shutters be closed as soon as the engine stops running, in order to conserve the heat in the engine, and also that the shutters remain closed after the starting of the motor, until the motor has reached a predetermined operating temperature. The ordinary thermostatic devices of the prior art require an appreciable time for cooling, so that the shutters of the prior art devices do not close promptly upon stopping the engine, and the prior devices which are actuated by suction from the exhaust manifold are uncertain in their action, since the suction is decreased by the opening of the throttle.

One of the objects of the present invention is the provision of a novel connecting mechanism, whereby shutters may be controlled responsive to conditions in a pair of different actuating or controlling devices.

Another object is the provision of an improved shutter control for internal combustion engines which is adapted to close the shutters as soon as the engine stops, and to open them only when the engine is both running and at a predetermined operating temperature.

Another object is the provision of a novel shutter control which is adapted to control the egress of the air from the engine enclosure, as well as the ingress responsive to the running condition of the motor.

Another object is the provision of an improved shutter control which is positively actuated by the pressure of oil from the oil pump usually employed for lubricating internal combustion engines.

Other objects and advantages of the invention will be apparent from the following description and from the accompanying drawings, in which similar characters of reference indicate similar parts throughout the several views.

Referring to the drawings, of which there are three sheets:

Fig. 1 is an elevational view in partial section, showing an internal combustion engine with an enclosure equipped with shutters and the present shutter control;

Fig. 2 is a medial sectional view in a vertical plane through the pressure responsive device of Fig. 1;

Fig. 3 is a similar view of the thermostatic device of Fig. 1;

Fig. 4 is a detail elevational view of the connecting mechanism in the normal position with the engine stopped and in a cold condition;

Fig. 5 is a similar view showing the connecting mechanism in a different position; that is, with the engine cold but running;

Fig. 6 is a similar view with the mechanism in the position assumed when the engine is hot but the motor has been stopped;

Fig. 7 is a similar view of the connecting mechanism with the shutters in open position, the mechanism being in the position which it assumes when the engine is both hot and running;

Fig. 8 is a detail elevational view in partial section taken from the inside of the hood or enclosure, showing the pressure actuated shutters for controlling the egress of the air from the side of the hood;

Fig. 9 is a sectional view taken on the plane of the line 9—9 of Fig. 8;

Fig. 10 is a sectional view taken on the plane of the line 10—10 of Fig. 8.

Referring to Fig. 1, 10 indicates in its entirety an internal combustion engine, which is provided with the usual hood or enclosure 11, dash board 12, pan 13, and radiator or front 14 for completely enclosing the internal combustion engine.

The present invention is of universal application to heat engines having a water cooling system or an air cooling system, but the embodiment chosen to illustrate the invention has a water cooling system, including a radiator 14 with the usual air passages 15 and water connections 16. The engine may be equipped with the usual fan 17, or in the case of airplanes, the fan may be omitted, as well as the water radiator.

The radiator 14 or front of the engine enclosure is preferably provided with a plurality of shutters 18, diagrammatically illustrated in Fig. 1, the shutters 18 being pivotally mounted at 19 in the shutter frame 20 having a fenestration 21. The shutters 18 are provided with rearwardly extending arms 22, a plurality of which are pivotally secured to a shutter actuating bar 23, and the shutters are urged to closed position by a coil spring 24 tensioned between frame 20 and shutter bar 23.

The shutter frame 20 may be provided with a bracket for pivotally supporting a bell crank 25 which is connected by a pin and slot 26 to the shutter bar 23, and the other arm of the bell crank 25 may be provided with a similar con-

nection to a rod 27, slidably mounted in a guide 28 carried by the radiator or shutter frame. The rod 27 is provided with a laterally turned end 29 forming a hook or journal adapted to be slidably and pivotally received in a slot 30 formed in a floating link 31.

The floating link 31 may comprise a flat piece of sheet metal provided with the elongated slot 30 for receiving the end of rod 27, and provided with a pair of spaced apertures 32 for receiving the laterally turned ends of connecting rods 33 and 34. The relation of the parts is such that when both the connecting rods 33 and 34 are actuated at the same time, the slot 30 is maintained in a position transverse to the direction of movement of the rod 27, and the rod 27 is actuated by the floating link 31, but when either of the connecting rods 33 or 34 is actuated separately, the floating link 31 tends to slide relative to the rod 27, and the end 29 of rod 27 slides to the opposite end of the slot 30. In some embodiments of the invention, the guide 28 may be eliminated, and the rod 27 is merely pivotally connected to the bell crank 25.

25. The connecting rods or links 33 and 34 are preferably provided with turnbuckles 35 and 36 for adjusting the effective length of the rods, and the other ends of the rods 33 and 34 are pivotally connected to bell cranks 37 and 38 to be actuated by a pressure responsive device 39 and a heat responsive device 40 respectively.

The heat responsive device 40 in the present embodiment is mounted directly upon the motor block 10, but if desired this element may be made responsive to the temperature of the radiator 14 or other parts which are heated by the engine. The heat responsive device 40 may comprise a metal casing 41 of substantially cylindrical shape and formed with an upwardly projecting lug 42 for pivotally supporting bell crank 38 by means of a rivet 43. One arm 44 of the bell crank 38 is pivotally connected to the laterally turned end 45 of connecting rod 34 while the opposite arm 46 is provided with a slot 47 for receiving a pin 48 carried by a plunger 49.

The casing 41 is preferably provided with an attaching flange 50 for securing the heat responsive device to engine block 10, by means of screw bolts 51, and the casing 41 is also preferably formed with a centrally located extension 52, forming a seat for a helical spring 53. The casing may also be provided with a sheet lining 54 of a size adapted to be received in the cylindrical casing 41 and adapted to slidably support a plurality of thermostatic wafers 55 of any conventional type. The extension 52 of casing 41 is provided with an axially located aperture 56 for slidably receiving the plunger 49, and the plunger 49 is threaded at its lower end to be received in a complementary threaded aperture in the thermostat engaging plate 57. At its upper end, the plunger 49 is enlarged and provided with a transverse pin 48, which pivotally and slidably engages in slot 47 of bell crank 38. The spring 53 is tensioned between the thermostat engaging plate 57 and the upper end of casing 41, tending to maintain the plate 57 in engagement with a central portion of the thermostatic wafers 55.

The pressure responsive device 39 may also consist of a cylindrical, cast metal casing 58 provided with a piston 59, slidably supported therein by a piston rod 60. The casing 58 is also provided with an upwardly extending lug 61 for pivotally supporting bell crank 38 by a rivet 62, one arm 63 of the bell crank having an aperture

for pivotally receiving the laterally turned end 64 of connecting rod 33.

The cylinder 39 may be provided with an axially located bore 65 for receiving piston rod 60, and a counterbore 66 for receiving packing 67. The counterbore 66 is threaded at 68 to receive the gland 69 for compression packing 67. The casing 58 may also be provided with an air aperture 70 above the piston 59 and with a threaded portion 71 adapted to be received in a complementary threaded bore 72 formed in a base 73. At any point near the bottom of the casing 58, it is provided with a threaded inlet aperture 74 adapted to receive a pipe fitting 75 for securing a metal pipe 76 in communication with the interior of casing 58 below piston 59.

The piston 59 may consist of a cup leather 77 having a pivotal outer flange 78 for engaging the walls of cylinder 58 and the cup leather 77 may be secured to piston rod 60 by riveting the cup leather between a pair of metal plates 79 and 80, the latter plate being provided with a hub 81 having a threaded aperture for receiving one end of the piston rod 60. The upper end of the piston rod 60 is provided with a transverse pin 82 adapted to be slidably and pivotally received in slot 83 of the arm 84 of bell crank 37.

The metal pipe 76 is connected to the outlet side of an oil pump shown diagrammatically at 85 the conduit 76 being of sufficient size to transmit pressure from the oil pump 85 to the piston 59. The helical spring 86 tensioned between metal plate 80 and the upper end of casing 58 is of sufficient strength to return the piston 59 to the position shown in Fig. 2, forcing the oil back through conduit 76 when the oil pump 85 is not in operation.

The hoods 11 of the usual internal combustion engines are generally provided with louvres 87 at the side forming outlets for the air drawn through the radiator 14, and in order to completely enclose the internal combustion engine 10, I prefer to provide the louvres 87 with shutters 88 for closing the louvres 87 when the engine 10 is not running. The shutters 88 may consist of a single plate 89 of sheet metal of substantially rectangular form provided with a plurality of transversely extending slots 90 adapted to register simultaneously with a plurality of louvres 87. The louvres 87 comprise vertically extending slots in the hood 11, which are enlarged by bending outward the forward wall of each slot as shown in Fig. 10, and the hood is preferably provided with guides 91 for the plate 89, which may consist of a pair of strips of metal of substantially Z-shape, as shown in Fig. 10, having one flange riveted to hood 11 and another flange forming a guide for the plate 89.

The shutter plate 88 is preferably provided at one end with a hook or shoulder 92 adapted to be engaged by a latch 93 pivotally carried by hood 11, and the shutter plate is urged to closed position by a pair of helical springs 94, tensioned between the shutter plate 89 and the rivets 95 carried by hood 11.

At the end opposite from the hook 92 the shutter plate 89 may be formed with a laterally projecting flange 96 adapted to be engaged by the actuating plunger 97 of a pressure responsive device 98. The pressure responsive device 98 is enclosed in a casing 99, which communicates with the oil pump 85 by a conduit 100, and when the engine is started, the oil pressure transmitted by the conduit 100 fills the chamber 101, causing the pressure responsive device 98 to contract,

the plunger 97 moving shutters 88 to the open position. When it is desired to lock the shutters in open position, this may be accomplished by means of the latch 93.

5 The flange 96, which is adapted to be engaged by plunger 97, may also be provided with a downwardly and forwardly sloping flange 102 adapted to cam against the plunger 97 when the side of the hood is moved down into closed position 10 after the hood has been opened.

10 The operation of the present shutter controlling device is as follows:

When the engine is not running and the engine parts are cold, the shutters are maintained 15 in closed position by the springs 24 and 94, which constantly urge the shutter bar 23 upward and shutter 88 rearwardly and the actuating devices 39 and 40 are in the position shown in Figs 2 and 3.

20 When the engine is started, the oil pressure from the pump 85 is transmitted by means of the conduit 76 to the cylinder 58, the oil pressure forcing the piston 59 upward and rotating bell crank 37 counterclockwise in Figs. 1 and 2. The arm 63 of bell crank 37 will exert a pull upon connecting rod 33, which will tend to open the shutters 18 against the tension of spring 24, but as soon as the slot 39 of floating link 31 assumes a position other than the vertical position, shown 25 in Fig. 4, the floating link 31 will slide upward on the end 39 of rod 27, assuming the position shown in Fig. 5.

30 Further pull exerted upon the connecting rod 33 will have substantially no effect upon the shutters 18, the floating link 31 merely pivoting about the end 39 of rod 27.

35 In a similar manner, when the thermostatic device 40 is actuated without actuation of the pressure responsive device 39, a pull being exerted on connecting rod 34 only, the end 39 of rod 27 slides to the upper end of slot 39 in floating link 31, and the floating link assumes the position as shown in Fig. 6. Thus, when the engine has been running and has been heated to 40 a predetermined temperature, the shutters will be closed promptly as soon as the engine stops, due to the cessation of pressure in the pressure responsive device 31.

45 When the engine is started, the connecting mechanism is moved to the position of Fig. 5, but the shutters are maintained in closed position by spring 24. The engine then continues to operate with the shutters closed until it has reached a predetermined temperature, which may be 50 approximately the most efficient operating temperature, after which the heat conducted from the engine will expand the thermostatic wafers 55, moving the plunger 49 upward in Fig. 3, rotating bell crank 38 counterclockwise and exerting a pull upon connecting rod 34. The floating link 31 will then pivot about the fulcrum provided by one end of the rod 33, the floating link moving in a clockwise direction from the position of Fig. 5 to that of Fig. 7, and the link 31 will exert a pull upon rod 27, pivoting bell crank 25 counterclockwise, moving shutter bar 23 downward and pivoting shutters 18 counterclockwise to the open position shown in Fig. 7.

55 If the engine should be stopped at this time, the cessation of pressure at the oil pump 85 and in the cylinder 58 will permit the springs 24 and 86 to return the shutters to closed position at once as shown in Fig. 6.

60 The shutters 88 at the side louvres of the hood 75 are also actuated by the pressure responsive

device 98, being open when the engine 10 is running and being closed as soon as the engine stops, so that the present device is adapted to completely enclose the engine as soon as it stops to conserve as much of the heat as is possible to insure easy starting of the motor. 5

65 It will thus be observed that the present radiator shutter control is adapted to be actuated responsive to two separate devices, which may consist of a pressure responsive device which is actuated responsive to the running condition of the motor, and a thermal device actuated at a predetermined engine operating temperature. The connecting mechanism is adapted to open the shutters only when the engine is running 15 and has simultaneously reached a predetermined temperature, and the shutters are promptly closed as soon as the engine either stops or drops below the predetermined temperature required for actuation of the thermostatic device. 20

70 While I have illustrated a preferred embodiment of my invention, many modifications may be made without departing from the spirit of the invention, and I do not wish to be limited to the precise details of construction set forth, but 25 desire to avail myself of all changes within the scope of the appended claims.

75 Having thus described my invention, what I claim is new and desire to secure by Letters Patent of the United States, is:

80 1. In a shutter control for internal combustion engines, the combination of a pair of independent shutter actuating devices with a plurality of shutters, and means connected to said shutters and to both actuating devices, adapted 35 to actuate said shutters responsive only to the movement of both said devices, but not responsive to the movement of either device alone.

85 2. In a shutter control for internal combustion engines, the combination of a thermostatic device for actuating shutters, and a device responsive to the running of the engine for actuating shutters, with a plurality of shutters, and means connected to said shutters and to both actuating 40 devices, adapted to actuate said shutters responsive only to the movement of both said devices, but not responsive to the movement of either device alone. 45

90 3. In a shutter control for internal combustion engines, the combination of a plurality of shutters for controlling flow of cooling fluid about parts of an internal combustion engine, with a spring for moving said shutters in one direction, a pair of controlling devices, and a mechanism 50 connected to both said devices and to said shutters, actuated by both said devices but not responsive to actuation by either controlling device alone. 55

95 4. In a shutter control for internal combustion engines, the combination of a plurality of shutters for controlling flow of cooling fluid about parts of an internal combustion engine, with a spring for moving said shutters in one direction, a pair of controlling devices, a floating link connected to both said devices and having a lost motion connection with said shutters whereby 60 said link actuates the shutters only on actuation of both said devices. 65

100 5. In a shutter control for an internal combustion engine, the combination of an enclosure about said engine, with a group of shutters for the front of said enclosure, an oil pressure device for actuating said shutters, a second group of shutters for the side of said enclosure, said second 70 75

group of shutters being actuated by said pressure device, and thermal means for controlling actuation of one of said groups of shutters by said pressure device.

5. In a shutter control for internal combustion engines, the combination of an enclosure with an internal combustion engine, said enclosure having a movable part for access to said engine, a pressure responsive device carried by said engine, and a plurality of shutters carried by said movable part and adapted to be actuated by said device when said part is in closed position.

10. In a shutter control for internal combustion engines, the combination of an enclosure with an internal combustion engine, said enclosure having a movable part for access to said engine, a pressure responsive device carried by said engine, a plurality of shutters carried by said movable part and adapted to be actuated by said device when said part is in closed position, a spring 15 for urging said shutters to closed position and means for latching said shutters in open position.

20. In a shutter control for internal combustion engines, the combination of a plurality of shutters with a slidably mounted part for actuating said shutters, a pivot post on said part, a link having a slot to receive said pivot post, a pair of links pivoted to said link whereby said shutters are actuated by a simultaneous actuation of 25

said pair of links, and a pressure responsive device actuated by oil pressure from the engine for actuating one of said pair of links.

9. In a shutter control for an internal combustion engine, the combination of a plurality of 5 shutters with a slidably mounted part for actuating said shutters, a pivot post on said part, a link having a slot to receive said pivot post, a pair of links pivoted to said link whereby said shutters are actuated by a simultaneous actuation of said pair 10 of links, a pressure responsive device actuated by oil pressure from the engine for actuating one of said pair of links, and a thermostatic device actuated by heat from the engine for actuating the other of said links.

15. In a shutter control for internal combustion engines, the combination of an enclosure with an internal combustion engine, a pair of independent shutter controlling devices, and a connecting mechanism between said shutters and 20 controlling devices comprising a slidably mounted part for actuating said shutters, a pivot on said part, a link having a slot to receive said pivot post, and a pair of links pivoted to said first mentioned link and connected to said independent controlling devices, whereby said shutters are actuated only by simultaneous actuation of 25 said pair of links.

FREDERICK C. BARGAR.
